ATTORNEY

UNITED STATES PATENT OFFICE.

CHARLES G. NESSLER, OF NEW YORK, N. Y.

HAIR-WAVING APPARATUS.

Application filed July 11, 1923. Serial No. 650,783.

To all whom it may concern:

Be it known that I, CHARLES G. NESSLER, a citizen of the United States, residing in New York, in the county of New York and

5 State of New York, have invented certain new and useful Improvements in Hair-Waving Apparatus, of which the following is a specification.

My invention relates to mechanism used 10 in the art of permanent waving of natural hair on the head, and my present improvements comprise portable apparatus equipped with a large number of heaters, preferably of the electric type, which may be easily 15 and quickly moved from one operating compartment to another, carrying its complete equipment, so that a single apparatus may be made to serve to carry out in succession the hair waving operation in a number of 20 separate booths or compartments, in each of which a customer may be awaiting her turn for the application of the set of heaters to her hair, which in the meantime may be made ready in advance for this part of the 25 process. The apparatus is preferably provided with wheels in order to make it readily movable from place to place, and in one form it is especially adapted for being positioned close to the back of a chair in 30 which the subject is seated. The invention also comprises certain means for effecting the vertical adjustment of the holder or head which supports the vertically adjustable heaters; also the construction and ar- 35 rangement of the heater-suspending canopy; also the construction of the heater-suspending and adjusting means, whereby the usual counterweights for the heaters are dispensed with; and certain other features as well as 40 details, all as hereinafter fully described and then pointed out in the claims.

I have illustrated a type of my improved apparatus in the accompanying drawings, wherein;

45 Fig. 1, is a perspective view of the apparatus and a chair near the back of which the apparatus is positioned.

Fig. 2, is an enlarged view of the lower 50 part of the apparatus including the wheeled-base and the adjustable support for the heater suspending head, part of the support being broken away and part in vertical central section.

Fig. 3, is a cross-sectional view of the telescoping support, the plane of the section being indicated by the line 3-3, in 55 Fig. 2.

Figs. 4 and 5, respectively, are similar cross-sectional views of the support, the planes of said sections being indicated by 60 lines 4-4, and 5-5, in Fig. 2.

Fig. 6, is an enlarged view of the upper portion of the apparatus, showing the upper part of the adjustable support and the heater-suspending head attached thereto. 65

Fig. 7, is a view in still greater enlargement, of one of the spring-actuated adjustable heater suspending devices which are mounted in the head, the view being in vertical section on a plane indicated by line 70 7-7, in Fig. 8.

Fig. 8, is a top plan view of a portion of the heater suspending head.

Fig. 9, shows an edge view of one of the 75 spring-actuated adjustable heater suspending devices, partly broken away, and on the same scale as that shown in Fig. 7.

Fig. 10, is an elevational view of a modified form of the apparatus in which the adjustable vertical support is omitted and the 80 heater suspending head is mounted directly on the ceiling of a room.

Referring to the drawings, 1 indicates a base which is oblong and three cornered in shape with a wheel 2, fixed upon the under 85 side at each corner for sustaining the base and permitting it to be trundled from point to point in shifting the apparatus about. The end 3, of the base is relatively narrow so that it may enter between the legs of the 90 chair 4, at the rear thereof, to permit of the apparatus being positioned adjacent the chair back. At the broad end of the base is mounted a telescoping adjustable support

5, consisting in a tubular post 6, bolted to 95 the base by a bracket 7, which extends upon the upper face and around the side of the base, as shown, to insure the stability of the post. A hollow upright 8, is mounted on the post so as to be vertically adjustable 100 thereon. The upright has a telescoping relation with the post, the lower end of the upright moving up and down inside of the post, which upon its interior is provided with a vertical rack 9, the post having a longitudinally extending enlargement 10, to accom-

modate the rack. This rack is constantly engaged by a pawl 11, pivoted at 12, to a sleeve 13, secured to the bar or upright 8, by a screw 14, see Fig. 4. A spring 15, secured to the pawl 11, bears with one end against the bar 8, and keeps the pawl in engagement with its rack 9. The upright 8, is provided with a pair of oppositely projecting handles 16 and 17, having screw-
5 threaded stems 18 and 19, respectively, which screw into threaded sockets in the laterally projecting bosses 20 and 21, on the sleeve 13. When the upright is to be raised or lowered, the handles 16 and 17 are grasped
10 by the operator who then lifts or lowers the upright, as the case may be. In lifting the upright to adjust it, the pawl 11, snaps over the teeth of the rack and the two serve to hold the parts in adjusted position. When
15 the upright 8, is to be lowered, the handles 16 and 17, are grasped and at the same time the finger pieces 22 and 23, are seized by the fingers of the operator, and drawn slightly to one side in order to release the
20 pawl from its rack, whereupon the upright may be lowered to the desired point while the pawl is held out of engagement. Upon releasing the finger pieces, the pawl automatically engages the rack and holds the up-
25 right in the position to which it has been dropped. The pawl 11, is yoked-shaped and spans the bar 8, as shown more particularly in Figs. 4 and 5. The opposite sides of the
30 tubular post 6, are formed with longitudinal slots 24 and 25, for the handles 16 and 17, respectively, to travel through.
35

Upon opposite sides of the upright 8, but at different levels, I provide antifriction rollers 26 and 27, for rendering the vertical movements of the upright smoother and also to maintain it in vertical position. These rollers are mounted to turn freely on bearings in the tubular post 6, and are grooved on their peripheries to fit the contour of the cylindrical upright 8, against which they bear upon opposite sides thereof.

50 bear upon opposite sides thereof. The holder or head 28, from which a large number of electric heaters 29, are adjustably suspended, is sustained in horizontal position by the supporting upright, by means of a horizontally projecting arm 30, connected with the bar 8, by an elbow fixture 31, adapted to detachably receive the electric wire coupling or plug 32, which is mounted 55 at one side thereof, as shown in Figs. 1 and 6. The electric wires pass thence through the hollow interior of arm 30, and through the elbow pipe 33, at the end, which pipe is secured to the center of the head 28, and 60 supports the same. The wiring, which is not fully shown, leads thence to the various electric connecting sockets upon the under side of the canopy and with which sockets the detachable plugs 34, are connected. The 65 electric wires 35, running from plugs 34,

lead to the suspended heaters 29, and supply the current thereto for heating the connected heaters.

The holder or head 28, comprises a central drum or box 36, in which are arranged the electric sockets 37, which open upon the under side thereof, as shown in Fig. 1. To the upper side of this central drum is detachably secured the elbow-pipe 33, of the support, the elbow being threaded at 38, for such attachment. A spider 39, is secured to the drum and its respective members are connected at their ends by means of screws 40, to an annular ring 41, upon opposite faces of which are mounted a series of U-shaped plates or brackets 42, 43, which carry at their upper ends bearings 44, 45, respectively, for the spring-winding pulleys or drums 46. A suspending cord or cable 47, is fastened to each of said drums which wind it up and pay it out, and the cord is connected at its other end with an electric heater 29. The drums are each provided upon their interiors with coiled springs 48, which act to wind the cord on the drum whenever the cord is relieved of the suspended weight of its heater, for example, when the operator takes the heater in his hand and lifts it, but this winding up action is under control of a special device 49, around which the cord is passed and which binds or clutches the cord to check its winding up movement, at the same time leaving the cord free to be drawn out or unwound by pulling upon it. This clutch device consists in an arbor 50 mounted to turn in bearings in the lower part of the drum bracket 42. The arbor is concave on its periphery so that it slopes from its respective ends to the center in order to crowd or force the turns 51, of the cord laterally together to form a bite or give the desired clutching action thereto. The cord 47, is passed around the arbor so as to give one full turn and part of another, as indicated in Figs. 7 and 9, at 51. A ratchet wheel 52, is made fast to the arbor 50, and is engaged by a gravity pawl 53, which prevents the arbor from being rotated backwardly by the winding drum. By this arrangement, the weight of the attached heater keeps the cord clutched around the arbor with sufficient force to prevent its racing or running off backwardly under the tension of the winding-drum spring, but as soon as the weight of the heater is taken off the cord by lifting the heater by hand, the clutching action of the turns of the cord on the arbor is released and the winding-drum's pull on the cord will slide it on itself around the arbor and cause the drum to wind on the cord as long as the heater is raised up towards it. In adjusting the heater to a lower position the operator pulls down upon the cord as he seizes the heater and this unwinds the

cord from the drum and also the clutch as the ratchet 52, is free to move in a forward direction on its axis. The suspending cords 47, each pass through an orifice 54, a series 6 of which are formed in the bottom plate 55, of the canopy, as indicated in Fig. 7. An annular outer rim or band 56, is mounted on the upper surface of the annular bottom plate 55, at the edge of the latter, which 10 is itself secured at its inner edge to the periphery of the central drum at 57. The two rows of brackets 42 and 43, are mounted by means of bolts 58, upon the annular member 41, and on opposite sides thereof, with 15 their lower ends resting upon the bottom plate 55. Several of the brackets 43, of the outer row, have their lower parts provided with an extension 59, having a horizontal flange or ear 60, which is bolted to the bottom plate 55, and a lateral flange or ear 61, which is bolted to the rim or band 56, and this serves to secure said parts firmly together.

The construction and arrangement of the 25 holder or head which I thus provide is simple and very compact and presents a neat and attractive appearance, especially for the portable or wheel-about type of apparatus, as herein shown. Moreover, I dispense with 30 the old form of counter-weights which are not only objectionable in appearance, but are at times in the way in their dangling and exposed positions. The construction of 35 the head and particularly its supporting arm and its elbow fixtures comply with the requirements of the underwriters.

In Fig. 10, I show a modification of the apparatus in which the movable stand is omitted and the holder or head 28^a, is secured directly to the ceiling 62, of a room, in which position it is out of reach of the operator, so that I lower the central drum 36^a, and fix it upon the end of a depending support 63, attached to the head so that the 45 detachable electric plugs 34^a, are easily within reach.

In order to stabilize the apparatus and to check any tendency of the weight of the laterally extending head tipping the apparatus over or unbalancing it. I dispose 50 the support 6, so that it is eccentric and is arranged at one end of the base, while the other end of the elongated base is arranged directly beneath the over-hanging head. 55 The unobstructed end 8, of the base is especially designed to be entered between the rear legs of a chair 4, so that the apparatus may be wheeled up close to the back of the chair in which the subject is seated, and 60 this affords an important facility in this class of apparatus. I also find that the improved wheel-about type of the apparatus permits the use of a large number of electric heaters for waving hair, in places and booths 65 where it is not possible to use the ordinary

chandellier type of mechanism, and this is an additional advantage to that of enabling the operator to trundle or wheel the entire apparatus about his establishment, from place to place and thereby employ but a single apparatus for use at different places, instead of having stationary apparatus at several places. The apparatus may be knocked-down or taken apart for placing it in a package to store or transport it. 70 75

Having thus described my invention, what I claim and desire to secure by Letters Patent is:

1. In portable apparatus for waving hair, a movable base having an upright support 80 secured to one end thereof so as to leave the main part of the base unobstructed, a heater-carrying head provided with depending heaters and mounted on said support to the side thereof where the main unobstructed part of said base is disposed so as to overhang said part of the base, said base resting upon the floor and constructed and arranged so that said unobstructed part thereof 85 which the said head overhangs may be entered beneath the seat on which the subject sits and thereby position said heater-carrying head over the head of the seated subject. 90

2. In portable apparatus for waving hair, 95 an elongated wheeled base, an upright support for the heater-carrying head mounted at one end of said base so that practically the entire length thereof is unobstructed, a head having a plurality of vertically-adjustable heaters suspended therefrom, said head mounted on said support and projecting laterally therefrom in the direction in which said base extends therefrom so that said head overhangs said base, thereby permitting a seat for the subject to be interposed between said base and head to position the latter over the subject. 100 105

3. In apparatus for waving hair, a head having a plurality of vertically adjustable electric heaters suspended therefrom, said head comprising a casing having a bottom and sides, a plurality of electric contacts arranged centrally in said casing, the said electric-heaters being adjustably suspended from said casing at points around said central electric-contacts and having electric connections with said contacts. 110 115

4. In apparatus for waving hair, a head having a plurality of vertically adjustable electric-heaters depending therefrom, the said head comprising a casing having a bottom and sides forming a comparatively shallow enclosure, a plurality of electric-contacts arranged centrally of said casing, the bottom of said casing having a plurality of perforations disposed around said group of electric-contacts, supporting devices for said electric-heaters arranged within said casing and having adjustable suspending cables extending through the respective perforations 120 125 130

- and connected with said electric-heaters, and said electric-heaters having electric connections with said electric-contacts.
5. In apparatus for waving hair, an upright support provided with wheels for sustaining it and permitting its being trundled from point to point, a head mounted on said support, heaters suspended from said head and provided with spring-actuated winding drums and cooperating cables for vertically adjusting said heaters, and means for holding the heaters in adjusted vertical positions.
6. In apparatus for waving hair, an upright support provided with ground-wheels for trundling the support from place to place, a head mounted upon said support and projecting laterally therefrom, spring-actuated winding-drums on said head, winding cables on said drums and heaters suspended from said cables, means for preventing the drums from winding on the cables when the weight of the heaters are imposed on said cables and permitting the drums to wind on said cables when the weight of said heaters is relieved by hand, whereby said heaters may be elevated in close proximity to the canopy leaving a free space beneath for clearance.
7. In apparatus for waving hair, a head, a set of spring-actuated winding-drums mounted on said head, a heater-suspending cable attached to each drum and wound thereon by the action of the spring when the cable is relieved of the weight of its heater, means for preventing the drum from winding on its cable when the weight of its heater is imposed on said cable.
8. In apparatus for waving hair, a head, a set of spring-actuated winding-drums mounted on said head, a heater-suspending cable attached to each drum and wound thereon by the action of the spring when the cable is relieved of the weight of its heater, a one-way acting clutch device for each cable which is coiled more than one turn around a one-way turning part of said device, whereby said device acts to stop the winding on of the cable by its drum while the weight of its heater is imposed on said cable, but permits the drum to wind on its cable when the weight of its heater is taken from said cable.
9. In apparatus for waving hair, a head, a set of spring-actuated cable-winding drums mounted on said head, a heater-suspending cable secured to each drum and wound thereon by the action of the spring when the cable is relieved of the weight of its heater, a one-way acting clutch device for each cable comprising a rotating shaft provided with a fast ratchet wheel, a pawl engaging said ratchet wheel, said cable being coiled around said shaft for more than one turn.
10. In apparatus for waving hair, a head, concentric rows of spring-actuated drums mounted thereon, a heater-suspending cable attached to each drum and wound thereon by the action of the spring when the cable is relieved of the weight of its heater, a one-way acting clutch device for each cable, a heater attached to each cable, a strip arranged on said head, and brackets on which said drums are mounted, said brackets being mounted on said strip.
11. In apparatus for waving hair, a head, a set of electric-sockets mounted centrally of the head, a set of spring-actuated winding-drums mounted on said head around the set of electric-sockets, a heater-suspending cable attached to each of the drums and wound thereon by the action of its spring when the cable is relieved of the weight of its heater, a heater attached to each of said cables, and means for preventing the winding of the cable on the drum when the weight of the heater is thrown on its cable.
12. In apparatus for waving hair, a head comprising centrally disposed means provided with a set of electric sockets, a set of spring-actuated winding drums, a plate on the under side of said head and upon which said drums are carried, a heater-suspending cable attached to each of said drums and wound thereon by the action of the spring when the weight of the heater is taken from its cable, a heater attached to each cable.
13. In apparatus for waving hair, a head for sustaining a set of vertically adjustable heaters comprising a bottom plate, a marginal band mounted upon the upper side of said plate, a set of spring-actuated winding drums mounted above said plate, a heater-suspending cable attached to each of said drums, a heater suspended from each cable, and a set of electric-sockets carried by said head.
14. In apparatus for waving hair, a head for sustaining a set of vertically adjustable heaters comprising a flat box-like structure provided with a bottom-plate and a marginal band mounted upon the upper side of said plate, a central compartment above said plate provided with electric connections, a spider attached to the upper side of said head, and a tubular support secured to said spider and adapted to receive electric-wire connections.
- In testimony whereof, I have hereunto set my hand.

CHARLES G. NESSLER.
